UNITED STATES PATENT OFFICE.

EDWARD BONK AND MICHAEL PLOTKA, OF CHILTON, WISCONSIN.

CAN-HANDLING DEVICE.

1,252,226.

Specification of Letters Patent. Patented Jan. 1, 1918.

Application filed September 12, 1917. Serial No. 191,061.

To all whom it may concern:

Be it known that we, EDWARD BONK and MICHAEL PLOTKA, citizens of the United States, residing at Chilton, in the county of Calumet and State of Wisconsin, have invented new and useful Improvements in Can-Handling Devices, of which the following is a specification.

This invention comprehends the provision of a fork designed for handling a large number of open top cans, and is particularly useful in unloading a car of cans without injuring the hands, or for feeding cans in large numbers to a track or conveyer in a factory.

More specifically stated, the invention embodies a plurality of prongs, so arranged that a certain number of prongs of each row will enter one can of a row of cans, and when the prongs of one row are separated from the prongs of the adjacent row, the cans are effectively held upon said prongs for the convenience of handling a large number of cans at one time.

The nature and advantages of the invention will be better understood when the following detail description is read in connection with the accompanying drawings, the invention residing in the construction, combination and arrangement of parts as claimed.

In the drawings forming part of this specification like numerals of reference indicate similar parts in the several views and wherein:—

35 Figure 1 is a perspective view of the fork showing the normal position of the component parts thereof.

Fig. 2 is a similar view showing the position of the prongs for holding cans thereon.

40 Fig. 3 is a transverse sectional view taken on line 3—3 of Fig. 1.

Fig. 4 is a view showing a row of cans, and the position of the forks prior to association of the latter with the cans.

45 Fig. 5 is an elevation showing the manner of supporting the cans with the forks.

Fig. 6 is a sectional view through one of the cans showing the position of the forks therein for supporting the same.

50 The device forming the subject matter of our invention as shown in this specific instance embodies two elongated strips 10 and 11 respectively with the latter being hingedly connected to the strip for pivotal movement with respect thereto, the hinges being indicated at 12. Projecting from the strip 10

are handles 13 which are suitably spaced apart, while projecting from the strip 11 are handles 14, the latter being disposed in juxtaposition to the handles 13, and in the same plane. Interposed between each pair of handles 13 and 14 respectively is a coil spring 15 which tends to maintain said handles spaced, and the strips 10 and 11 in face to face contact. Of course, one or two handles may be used.

Projecting from the strip 10 is a longitudinal series of spaced prongs 16, while projecting in the same direction from the strip 11 is a longitudinal series of prongs 17, the latter being spaced the same distance apart as the prongs 17 whereby the prongs of the respective strips will be arranged in pairs. The prongs 16 are relatively long compared with the length of the prongs 17 so as to maintain the cans solidly on the device but the prongs of each row being preferably covered with rubber or other suitable material 18 with a view of obtaining a better hold upon the cans in a manner to be presently described. It might here be stated, that the fork in its entirety may vary in size, and that the component parts of the invention may be constructed from any suitable material. And while we have shown and described but two rows of prongs, with the prongs of the respective rows disposed in parallelism, we desire to have it understood that we do not limit ourselves to this specific arrangement, and that different numbers of rows of prongs may be provided with the prongs in a somewhat staggered relation if desired.

As hereinabove stated the invention is particularly adapted for handling a large number of open top cans, and we have shown in Fig. 4 a row of such cans, with the fork positioned with respect thereto, just prior to the positioning of the prongs within the cans. It will be noted that each pair of the prongs 16 and 17 respectively are disposed in parallelism and closely associated, or when the fork is associated with the cans, one pair of these prongs enters each can. Then, by drawing the handles 14 in the direction of the handles 13, the strip 11 is moved about its pivot, thus separating the row of prongs 17 from the prongs 16. Consequently each pair of prongs 16 and 17 respectively within each can, assumes a divergent relation, bearing against the walls of the can in a manner to maintain the cans

fixed relatively to said prong. As long as the prongs are maintained in this position, the fork in its entirety can be supported vertically, horizontally, or in any other position without any danger of the cans becoming separated from the fork. As above stated the prongs are wrapped with rubber or other suitable material, so that when they are brought into contact with the walls of the can they take hold of the latter in the manner to prevent any relative movement or play between the can and the prongs positioned therein. When the cans have been lifted, and placed at their proper destination, it is only necessary to release the handles 14, when the springs 15 function to return the handles 14 to their normal position, during which time of course the strip 11 and the prongs 17 are brought toward each other to their normal position, and the fork can be subsequently easily and quickly separated from the can.

While it is believed that from the foregoing description the nature and advantages of the invention will be readily apparent, we desire to have it understood that what is herein shown and described is merely illustrative of one embodiment of the invention, to which we do not limit ourselves, and that such changes may be resorted to when desired as fall within the scope of what is claimed.

What is claimed is:—

1. A can handling device comprising a support, said support including a fixed section and a relatively movable section associated therewith, a row of prongs projecting from each section, yieldable means normally holding said sections in a position whereby the prongs of one row are disposed in parallelism with the prongs of the other row, the prongs of one row being relatively long with regard to the prongs of the other row, and means for adjusting said movable section whereby the rows of prongs assume a divergent relation.

2. A can handling device comprising a support including hingedly connected sections, a row of relatively long prongs projecting from one of said sections, a row of relatively short prongs projecting from the other of said sections and normally disposed in parallelism with the first mentioned row, yieldable means normally maintaining the rows of said prongs parallel, a covering of pliable material for each of said prongs, and means for changing the normal positions of said sections, whereby said rows of prongs assume a divergent relation.

60 3. A can handling device comprising a

support, including a fixed section, and a relatively movable section associated therewith, a row of prongs projecting from each section, the prongs of one row being relatively long compared with the prongs of the other row, a plurality of handles projecting from each section, and said handles being arranged in pairs, a spring interposed between each pair of handles and normally maintaining the sections positioned whereby the rows of prongs are arranged in parallelism, and said handles when brought together against the tension of said springs serving to cause said rows of prongs to assume a divergent relation for the purpose specified.

4. A device for handling a plurality of open top cans, comprising a pair of hingedly connected members, a row of prongs projecting from each member, said prongs being adapted to be positioned within the cans with one of said rods engaging the corresponding walls of the cans forming a support for the latter, and means whereby the other row of prongs may be moved into engagement with the opposite walls of said cans to hold the latter fixed relatively upon said prongs.

5. A device for handling open top cans, comprising a pair of hingedly connected members, a row of prongs projecting from each member and disposed in parallelism, one row of prongs being relatively long and adapted to engage against one wall of the cans when initially arranged within the latter, the other row of prongs being relatively short, and means whereby the latter mentioned row may be moved into engagement with the opposed walls of the cans, to engage the cans in a manner to retain the latter solidly arranged upon said prongs.

6. A device for handling open top cans comprising a pair of hingedly connected members, a row of prongs projecting from each member and disposed in parallelism, said prongs being adapted to be positioned within the cans with one row of prongs initially engaging one wall of the can, a handle projecting from each member, whereby the other row of prongs may be moved into engagement with the opposed wall of said can for holding the cans fixed upon said prongs, and yieldable means for returning the second mentioned prongs to normal position upon release of one of said handles.

In testimony whereof we affix our signatures.

EDWARD BONK.
MICHAEL PLOTKA.
